CLAIM

The ornamental design for an animal trap, substantially as shown.

DESCRIPTION

FIG. 1 is an elevational view from one side showing an animal trap embodying the ornamental features of my new design, the trap being in its sprung position; FIG. 2 is a similar view from the opposite side showing the trap in its set position;

FIG. 3 is a top view thereof;

FIG. 4 is a bottom view thereof;

FIG. 5 is a rear view thereof, and

FIG. 6 is a front view thereof.
